UNITED STATES PATENT OFFICE.

CHARLES F. HEATH, OF RUTLAND, VERMONT.

DRIVER OR DRAWER FOR DRAFTSMEN'S TACKS.

SPECIFICATION forming part of Letters Patent No. 590,760, dated September 28, 1897.

Application filed January 21, 1897. Serial No. 620,061. (No model.)

To all whom it may concern:

Be it known that I, CHARLES F. HEATH, a citizen of the United States, residing at Rutland, Rutland county, Vermont, have invented 5 an Improved Driver or Drawer for Draftsmen's Tacks, of which the following is a specification.

This invention relates to improvements in devices or tools for pressing in and drawing 10 out the broad-headed tacks employed by draftsmen to fasten down their paper; and the object is to provide a simple and inexpensive tool especially adapted for the purpose intended.

15 In the drawings, which illustrate two embodiments of the invention, Figure 1 is a perspective view of one form of the device. Fig. 2 is a front end view of the same. Fig. 3 is a side view of the same, and Fig. 4 is an under 20 side view of the same. Fig. 5 is a side view, and Fig. 6 a front end view, of the device in a form slightly different from that in the other figures. Fig. 7 comprises three illustrative views showing the manner of using the tool.

25 Referring to the first four figures of the drawings, which illustrate the invention in its simpler embodiment, the tool is formed of a single strip of flat metal bent into a loop-like shape or contour. The arch of the loop forms 30 a handle *a* and the lower part of the loop forms a convex or rocker base *b*. The projecting extremity *c* of the base is brought to an edge or sharpened and has in it a slit *d*, Fig. 4, to receive the body of the tack *x*, Figs. 35 2 and 7, in setting and drawing the latter. The other extremity *e* of the strip of metal over the slit *d* is bent back parallel with the slotted end and then shouldered down upon the base at *f*, where it is secured to the latter.

40 The shoulder at *f* forms a pocket *g*, Figs. 2 and 3, between the flat slotted extremity *c* and portion *e* above it, to receive the broad head of the tack *x*, the part *e* forming a roof-plate for the said pocket.

45 The advantages of the tool will be apparent to any draftsman, and the operation of setting and driving the tack will be readily understood from the illustrative view, Fig. 7. The tack *x* is placed in the tool with its body engaging the slit *d* and its head engaging the pocket *g*. The draftsman grasps the

handle *a* and places the convex base *b* on the paper substantially as in the upper view, Fig. 7. He then rocks the tool forward, rolling the creases from the paper and stretching it 55 properly to receive the tack. The middle view in Fig. 7 shows the tack set in the paper and board by the tool, and the lowermost view in said Fig. 7 shows the mode of driving the tack home after the tool is withdrawn 60 from it. To draw out the tack, the sharpened and slotted end *c* is passed under the head of the tack in such a manner that the body of the latter passes into the slit *d*, and the tool is then rocked on its convex base in such a 65 manner as to pry or lift the tack out.

Figs. 5 and 6 illustrate a form of the tool in which the loop-like handle is of cast metal, and there are two tack drawing and setting devices, one at each end, the slits being formed 70 in a separate plate of metal which forms the rocker-like base *b* and which is secured to the cast metal above it. This form provides a heavier and stronger tool than the one first described, but a more expensive one. The 75 two drawing devices may be adapted for different sizes of tacks, if desired.

Having thus described my invention, I would say that I do not broadly claim a tool or device for drawing out draftsmen's tacks 80 and having a sharpened extremity and a notch to engage the body of the same. Such devices are common, as are also devices of a similar kind for drawing out carpet-tacks; nor do I claim a tool for drawing out draftsmen's tacks having a flat surface to rest on the paper and a sharp elbow or bend for a fulcrum; but

What I do claim is—

1. As an improved article of manufacture, a 90 tack driving and drawing tool having a convex base and a sharpened and slotted extremity, and a loop-like handle which extends in the form of a loop from the slotted extremity to the opposite end whereby pressure 95 may be applied directly over the tack for driving it, substantially as set forth.

2. As an improved article of manufacture, a tack driving and drawing tool, having a convex, rocker-like base, one end of which is 100 sharpened and slotted as described, and a loop-like handle, a part of which extends over

said slit and forms the roof-plate of a pocket which receives the head of the tack, substantially as set forth.

3. A tool for driving and drawing tacks, comprising a single flat strip of metal bent into a loop-like contour and forming the handle *a*, and convex base *b*, and having a slit *d* in the end *e* of the base, a roof-plate *e* over said slit, and a shoulder *f*, which forms a

pocket *g*, to receive the tack-head, substantially as set forth.

In witness whereof I have hereunto signed my name in the presence of two subscribing witnesses.

CHARLES F. HEATH.
